HYDRAULIC GOVERNOR RAPID RESPONSE UNLOADING AND LOADING DEVICE

Thomas F. Cramer, Warren, Mich., assignor to Holley Carburetor Company, Van Dyke, Mich., a corporation of Michigan

Filed May 26, 1958, Ser. No. 737,777

10 Claims. (Cl. 123—103)

The present invention relates to a hydraulic governor rapid response unloading and loading device.

In engine speed governors responsive either to engine speed or to road speed of the vehicle, it is desirable to provide for positive actuation of the speed control element such for example as the engine throttle, by a positive acting motor and this may be readily accomplished by employing speed responsive means whose function is to control a valve which in turn controls the admission of hydraulic pressure to a hydraulic motor for effecting movement of the throttle. In some cases the hydraulic fluid is applied to a housing including a movable element such for example as a flexible diaphragm, and the oil in the housing opposes return movement of the diaphragm when it is required to load. This tends to prevent or retard throttle opening movement, thus resulting in poor response. In accordance with the present invention means are provided facilitating flow of oil from the chamber of the hydraulic motor, thus improving response.

Accordingly, it is an object of the present invention to provide hydraulic means for actuating a speed control member such for example as the throttle of an internal combustion engine, including a hydraulic motor, and means associated therewith to improve the response of the system to variations in speed.

It is a further object of the present invention to provide a speed control system for an internal combustion engine, preferably of an automotive vehicle, which includes means for supplying hydraulic fluid at a pressure variable in accordance with speed, either engine speed or road speed, means responsive solely to variations in pressure of the hydraulic fluid for controlling the admission of an hydraulic fluid under pressure to a fluid motor, and means responsive to manifold vacuum of the engine for exhausting fluid from the motor to provide rapid response during loading.

More particularly, it is an object of the present invention to provide a speed responsive engine control system including a fluid motor for regulating engine speed, speed responsive means for applying fluid under pressure to the motor upon an increase in speed above a predetermined minimum, and means responsive to engine manifold vacuum for controlling an exhaust flow of fluid from the motor.

Other objects and features of the invention will become apparent as the description proceeds, especially when taken in conjunction with the accompanying drawings, illustrating preferred embodiments of the invention, wherein:

Figure 1 is a diagrammatic sectional view of the components of the engine control system.

Figure 2 is a view similar to Figure 1 showing a second embodiment of the present invention.

Referring first to Figure 1 the internal combustion engine includes a manifold 10 having a carburetor connected thereto which include an inlet passage 12 provided with a venturi 14 in which is located a primary

2

fuel supply nozzle 16. Located in the intake passage is a choke valve 18 and downstream from the venturi 14 is provided the usual manually operable speed control throttle 20 which is pivoted as indicated at 22 and provided with an operating arm 24 connected by a link 26 to the usual speed control device such for example as the accelerator pedal. The automatic engine speed governor includes a passage insert portion 30 disposed between the carburetor intake passage 12 and the manifold 10 and in this insert portion is provided an automatic engine speed control throttle 32 which is carried by a shaft 34 having an arm 36 rigidly connected thereto, the arm being connected to an actuating rod 38 extending to a hydraulic motor indicated generally at 40.

15 The motor includes a flexible diaphragm 42 forming with a housing portion 44 a pressure chamber 46. The diaphragm 42 has its central movable portion connected to the link 38 and a compression spring 48 extends between the diaphragm and a spring seat 50 in the motor. 20 The space to the right of the diaphragm 42, as seen in Figure 1, is at atmospheric pressure.

Means are provided for supplying hydraulic fluid under pressure to the chamber 46 of the motor 40 and this means comprises a pump 52 which supplies hydraulic fluid through a constant pressure regulating valve 54 to an inlet passage 56 provided in a spinner type pump indicated generally at 58. The pump 58 includes a spinner element 60 adapted to be connected by suitable means such as gear 61a to a rotary driver such as gear 61b which may be driven at a speed variable in accordance with engine speed or which may be driven at a speed variable in accordance with road speed of the vehicle. In any case, the hydraulic fluid entering the passage 56 passes through the radial passages 62 of the spinner into the cylindrical chamber 64 of the pump 58 and establishes therein a pressure which is variable in accordance with the speed of rotation of the spinner. Hydraulic fluid under the pressure thus established in the chamber 64 is transmitted to the chamber 66 of a speed responsive regulating valve 68 through an external passage or conduit 69. The valve 68 includes a body portion or housing 70 and a cap 72 between which is clamped a flexible diaphragm 74, thus forming the chamber 66 between the diaphragm 74 and the cap 72. The space indicated at 76 below the diaphragm 74 may be vented to atmosphere as indicated at 78.

45 The valve 68 includes a passage 80 extending therethrough intercepted by a cylindrical valve chamber 82 in which is longitudinally slidable a spool valve 84 having a reduced intermediate portion 86. With the parts in the position shown in Figure 1 it will be noted that the reduced portion 86 is in registration with the passage 80 and accordingly, a free flow of fluid is permitted through the valve. Normally however, the valve is maintained in an upper closed position by a compression spring 88 the effectiveness of which may be adjusted by an abutment plug 90 threaded into a tubular extension 92 of the housing 70 and retained in adjusted position by a lock nut 94. The spring chamber is vented to the atmosphere as indicated at 89. The hydraulic fluid from the pump 52 as the pressure is regulated by the valve 54, flows through an external passage or conduit 96 to the valve 68 and, when permitted to do so by proper location of the spool valve 84, fluid flows from pump 54 through the valve and through an external passage or conduit 98 to the actuating chamber 46 of the motor 40.

60 With the parts in the position shown in Figure 1 it will be noted that the flexible diaphragm 42 is to the left although the reduced portion 86 of the valve is in position to allow a flow of hydraulic fluid under pressure to the chamber 46. This condition may exist because

hydraulic fluid entering the chamber 46 is allowed to exhaust therefrom through an exhaust port 100 controlled by a spool valve 102 having an intermediate reduced portion 104 which as shown is in registration with the port 100 and thus permits an exhaust flow of hydraulic fluid through an external passage or conduit 106, which may be connected to the sump which supplies the pump 52.

The position of the exhaust valve 102 is determined by a flexible diaphragm 108 the intermediate portion of which is connected by a rod 109 to the spool valve 102, the diaphragm being biased to the left as seen in Figure 1 by a compression spring 110 located in a chamber 112 provided by a cap 114 which clamps the periphery of the diaphragm to an annular portion of the motor 40. A fluid passage or conduit 116 extends from the interior of the chamber 112 to the interior of the insert portion 30 so that the chamber 112 is at all times subjected to the partial vacuum existing within the manifold 10 of the engine. The spool valve housing 103 may be connected to the sump through the ports 105 and 107 so as to return to the sump any hydraulic fluid escaping across the spool valve 102.

As the engine approaches governed speed the oil pressure in the chamber 66 increases due to the increased speed of rotation of the spinner 62. At governed speed pressure within the chamber 66 overcomes the spring 88 and permits the flow of hydraulic fluid to the chamber 46 of the motor 40. Below governed speed the spool valve 102 is in the position shown permitting hydraulic fluid to exhaust from the chamber 46 through the passage 106 back to the sump, crankcase or reservoir. However, when cutoff speed is reached, and the engine is unloading, manifold vacuum in the chamber 112 causes the diaphragm 108 to shift the spool valve 102 toward a position in which it closes the port 100. This movement decreases the effective size of the port 100 and allows rapid unloading of the engine as hydraulic fluid flows into the chamber 46.

When it is required to again load the engine, manifold vacuum is decreasing and the spring 110 moves the diaphragm 108 to cause movement of the piston 102 to a position in which its reduced portion 104 registers with the port 100, thus allowing oil to exhaust from the chamber 46, and allowing pressure in the chamber 46 to fall off rapidly, providing rapid loading of the engine.

Referring now to Figure 2 there is illustrated a similar arrangement and where applicable corresponding parts have been identified with the same reference numerals as in Figure 1 and will not again be described. In addition, the spinner element 60 may be driven through the same means described for the embodiment shown in Figure 1 including the gears 61a and 61b.

The arrangement in Figure 2 differs primarily in the provision of a somewhat different motor herein indicated at 120 having an actuating rod 122 connected to the arm 36 of the governor throttle plate 32.

The motor 120 comprises two casing parts 124 and 126 adapted to clamp the edges of a flexible diaphragm 128 therebetween to divide the motor 120 into an actuating chamber 130 and a second chamber 132 which may be vented to atmosphere as indicated at 134. A compression spring 135 is provided in the chamber 132 acting between the casing part 126 and the central portion of the diaphragm 128 to bias the diaphragm in a direction which results in full opening of the automatic throttle plate 32.

Associated with the motor 120 is a valve 136 comprising housing portions 138 and 140 which clamp between them the edge of a flexible diaphragm 142 dividing the interior of the valve into chambers 144 and 146. Located within the chamber 144 is an adjustable compression spring 148, the adjustment being effected by a reduced spring seat 150. The housing portion 140 of the valve 136 is open from end to end and has a valve

seat 152 therein which cooperates with a movable valve element 154 connected by a stem 156 to the central portion of the flexible diaphragm 142. The open end of the housing portion 140 to the right thereof as seen in Figure 2, connects with an opening 158 in the housing portion 124 of the motor.

An external passage or conduit 160 controlled by the spool valve element 84 of the speed responsive valve 68 supplies fluid to the chamber 130 when the speed of rotation of the spinner 62 is sufficiently high. Exhaust of the hydraulic fluid in the chamber 130 is past the valve element 154 and out an exhaust passage 162 which connects to an external passage or conduit 164 leading to the sump, reservoir, or crankcase. Accordingly, when the valve 154 is open pressure within the chamber 130 is insufficient to overcome the spring 135 and hence the automatic throttle plate 32 remains in open position.

The operation of this embodiment of the invention is substantially the same as that previously described.

The drawings and the foregoing specification constitute a description of the improved hydraulic governor rapid response unloading and loading device in such full, clear, concise and exact terms as to enable any person skilled in the art to practice the invention, the scope of which is indicated by the appended claims.

What I claim as my invention is:

1. An engine speed control system for a vehicle internal combustion engine having an intake manifold and an engine control throttle, said system comprising a fluid motor connected to the throttle, speed responsive means controlling the application of actuating fluid to said motor, and means responsive to manifold vacuum of the engine for controlling the effectiveness of the application of fluid pressure to said motor.

2. An engine speed control system for a vehicle internal combustion engine having an intake manifold and an engine control throttle, said system comprising a fluid motor connected to the throttle, said motor having an expansible actuating chamber, speed responsive means independent of engine load controlling the application of actuating fluid to said chamber, and an exhaust valve responsive to manifold vacuum of the engine for controlling the exhaust of fluid from said chamber.

3. An engine speed control system for a vehicle internal combustion engine having an intake manifold and an engine control throttle, said system comprising a fluid motor connected to the throttle, said motor having an expansible actuating chamber, a rotary fluid pump, means for driving said pump at a speed which is dependent on engine speed to supply hydraulic fluid at a pressure which is dependent on engine speed, valve means responsive to pressure of fluid supplied by said pump connecting a source of fluid pressure to said chamber to supply hydraulic fluid to said chamber, an exhaust valve connected to said chamber, and means responsive to engine manifold vacuum connected to said exhaust valve to control the same.

4. An engine speed control system for a vehicle internal combustion engine having an intake manifold and an engine control throttle, said system comprising a fluid motor connected to the throttle, said motor having an expansible actuating chamber, a rotary fluid pump, means for supplying hydraulic fluid to said pump at a constant pressure, means for driving said pump at a speed which is dependent on engine speed to supply hydraulic fluid at a pressure which is dependent on engine speed, valve means responsive to pressure of fluid supplied by said pump connecting a source of fluid pressure to said chamber to supply hydraulic fluid to said chamber, an exhaust valve connected to said chamber, and means responsive to engine manifold vacuum connected to said exhaust valve to control the same.

5. A throttle regulating hydraulic motor for an internal combustion engine having a throttle controlled inlet manifold, a hydraulic pump adapted to supply hy-

draulic fluid at a pressure dependent on pump speed, means for driving said pump at a speed dependent on engine speed, means including a valve responsive to the pressure of fluid delivered by said pump connecting said motor to a source of actuating pressure, a bypass valve controlling the application of hydraulic fluid to said motor, and means responsive to engine manifold vacuum connected to said bypass valve to control the same.

6. A throttle regulating hydraulic motor for an internal combustion engine having a throttle controlled inlet manifold, said motor having a chamber having a movable wall, speed responsive means independent of engine load controlling the application of actuating fluid to said chamber, means connecting said wall to said throttle to close said throttle upon expansion of said chamber by the actuating fluid, resilient means opposing expansion of said chamber, an exhaust valve for said chamber, and means responsive to engine manifold vacuum connected to said exhaust valve to control the same.

7. A governor for an internal combustion engine having an intake manifold and a throttle controlling flow of fuel mixture to said manifold, a hydraulic motor having an expansible chamber including a movable wall, means connecting said wall to the throttle to effect closing movement of said throttle upon expansion of said chamber, a source of hydraulic fluid under pressure, rotary pump means operated at a speed dependent on engine speed connected to said source and adapted to deliver hydraulic fluid at an increased pressure dependent on engine speed, means including a supply valve responsive to pump delivery pressure connecting said source and said chamber, resilient means opposing expansion of said chamber, and an exhaust valve responsive to manifold vacuum of the engine connected to said chamber.

8. A governor for an internal combustion engine having an intake manifold and a throttle controlling flow of fuel mixture to said manifold, a hydraulic motor having an expansible chamber including a movable wall, means connecting said wall to the throttle to effect closing movement of said throttle upon expansion of said chamber, a source of hydraulic fluid under pressure, rotary pump means operated at a speed dependent on engine speed connected to said source and adapted to deliver hydraulic fluid at an increased pressure dependent on engine speed, means including a supply valve responsive to pump delivery pressure connecting said source

5

and said chamber, said supply valve comprising resilient means effective to keep said supply valve closed at pressures less than that determined by a selected governed speed, resilient means opposing expansion of said chamber, and an exhaust valve responsive to manifold vacuum of the engine connected to said chamber.

9. A governor for an internal combustion engine having an intake manifold and a throttle controlling flow of fuel mixture to said manifold, a hydraulic motor having an expansible chamber including a movable wall, means connecting said wall to the throttle to effect closing movement of said throttle upon expansion of said chamber, a source of hydraulic fluid under pressure, rotary pump means operated at a speed dependent on engine speed connected to said source and adapted to deliver hydraulic fluid at an increased pressure dependent on engine speed, means including a supply valve responsive to pump delivery pressure connecting said source and said chamber, said supply valve comprising resilient means effective to keep said supply valve closed at pressures less than that determined by a selected governed speed, resilient means opposing expansion of said chamber, and an exhaust valve responsive to manifold vacuum of the engine connected to said chamber, said exhaust valve including resilient means opposing movement thereof occasioned by a reduction in engine manifold vacuum and operable to close said exhaust valve during unloading of said governor and to open quickly upon start of governor loading.

10. An engine speed control system for a vehicle internal combustion engine having an intake manifold and an engine control throttle, said system comprising a fluid motor connected to the throttle, speed responsive means independent of engine load controlling the application of actuating fluid to said motor, and means responsive to manifold vacuum of the engine for controlling the effectiveness of the application of fluid pressure to said motor.
